HAIR CLIPPING IMPLEMENT

Fred L. Hazelquist, Menlo Park, Calif.

Application January 17, 1952, Serial No. 266,816

20 Claims. (Cl. 30—201)

The present invention relates to improvements in clippers of the oscillatory type and particularly to a power operated clipper having a cutting member movable fore and aft as well as laterally over a fixed comb.

The purpose of this combination and arrangement of parts is to provide a single, handy barbering device which may be easily and safely held and used in one hand, by a novice, in executing any and all of the usual hair arranging and picking up operations preparatory to cutting the hair as performed with two hands, by a skilled barber. In other words, the primary object of my invention is to provide a combined power clipper device and fixed comb for use in first picking up the hair and then cutting and/or trimming the hair as arranged and held by the fixed comb in lieu of the usual separate barber's shears and comb, and with far greater facility, accuracy and speed than can be performed other than by a skilled barber.

Another object of my invention, therefore, is to provide a power clipper with a comb-type blade which is rigidly fixed thereto to extend outwardly therefrom at approximately 45 degrees to the axis thereof, so that the operative face of the comb be readily visible to the user for both combing and cutting operations, and to provide a slidable support and cooperating cutting member for the clipper blade at various points thereon.

A further object of my invention is to provide such a combined device in which the comb teeth are of the usual long length for proper hair picking up and combing operations and the teeth of the clipper mechanism are relatively short and are mounted on the operative face or body of the comb for free to and fro sliding movements, as well as transverse sliding movements, from a non-hair cutting position on the comb body adjacent the base of the comb teeth, to any desired hair clipping association with the comb teeth, throughout the entire length thereof, to their outer free ends.

A still further object of my invention is to provide a hair cutting and trimming implement which is also selectively usable as a hair comb and a hair clipper.

Another object of my invention is to provide a combined hair-combing, trimming and clipping implement, in which the disposition of the handle providing body and the hair combing and cutting mechanisms are so arranged and disposed as to increase the user's vision and control of the implement and thus provide a greater measure of confidence and assurance in his ability to perform a first-class hair trimming and/or cutting job.

Another object of my invention is to provide a device of the above noted character in which the power operated clipper is spring biased to a normal non-hair clipping position on the comb body and wherein a thumb or finger operated lever is provided to slide the clipper mechanism, at the will of the user, to and from said non-hair cutting position on the comb body and to and from the free ends of the comb teeth, the unitary device being usable in such a manner that the comb and clipper mechanisms may be selectively used and controlled by the same hand that holds and directs the device for operation.

2

It is, therefore, the purpose and object of my invention to provide a power operated barbering device to take the place of the usual separate shears and comb, which is of simple and efficient construction and which may be easily held, operated and controlled by one hand of the user; whereby to skillfully, speedily and safely manipulate the device through the hair as a barber's comb and in full view of the user, to pick up the hair in the comb to the desired depth and arrangement and to thereafter advance the clipping mechanism from a non-hair cutting position to any desired point on the comb to evenly and accurately trim and/or taper the hair so as to produce the desired blending to the contour of the head.

A still further object of my invention is to provide a barbering device of the above noted character which does not require any initial adjustments for any cutting operation, style or length of hair cut.

A still further object of the invention is to provide a power operated hair cutting device embodying a fixed comb and a cutting blade relatively movable thereto, and wherein the blade is capable of instant removal by the fingers of an operator, thereby facilitating the cleaning of the cutting blade, as well as replacement thereof, should occasion demand.

A still further object of my invention is to provide a power operated hair cutting device embodying a comb having a plane working surface and a cooperating cutting blade movably supported on the comb working surface and wherein the cutting blade is of minimum weight, pressed sheet metal construction and which is outwardly arched intermediate its cutting edge and an opposed bearing edge thereby reducing friction to a minimum as well as providing for the circulation of cooling air between the arched portion and the comb working surface.

A still further object of the invention is to provide a power operated hair cutting device of the character above referred to which is provided with simple and efficient means for lubricating the cooperating bearing surfaces of the comb and cutting blade.

The foregoing recited objects and advantages, together with any subsequent features that may be developed in the specification and claims, constitute my invention, two embodiments of which are shown in the accompanying drawings, in which:

Fig. 1 is a vertical longitudinal sectional view in the plane of line 1—1 on Fig. 5 and with the motor housing or handle broken away, the oscillatory cutting blade being shown in normal inoperative position;

Fig. 2 is an elevational view of the supporting plate which is attached to the forward end of the motor housing or handle and with structure, later described, added, the view being in the plane of line 2—2 on Fig. 1;

Fig. 3 is an inner or rear elevational view of the vibratory plate and the associated cutter blade controlling plate hingedly supported thereby and being substantially in the plane of line 2—2, but observed in a direction opposite to the arrows thereon, and with certain structure removed;

Fig. 4 is an outer elevational view of the cutter blade controlling plate;

Fig. 5 is a front elevational view as observed in the direction of arrow 5, in Fig. 1;

Fig. 6 is a side elevational view of the improved implement on actual scale size, the previously described views being on a substantially enlarged scale;

Fig. 7 is a broken side elevational view similar to Fig. 6, but wherein the comb is substantially of the straight tooth form of the usual hair comb;

Fig. 8 is a broken side elevational view showing the device with the oscillatory cutting blade in the normally inoperative position of Fig. 1, and resulting use of this improved device in a combing operation;

Fig. 9 is a view similar to Fig. 8, but showing the de-

vice as having completed the hair picking up operation of Fig. 8, and subsequent cutting operation by advancing the clipper member;

Fig. 10 is a top plan view of the improved light weight pressed sheet metal cutting blade;

Fig. 11 is a bottom plan view of the blade;

Fig. 12 is a transverse sectional view of the blade as observed in the plane of line 12—12, on Fig. 10;

Fig. 13 is a further transverse sectional view as observed in the plane of line 13—13, on Fig. 10;

Fig. 14 is an elevational view corresponding to Fig. 3 and disclosing improved lubricating means for the relatively movable parts;

Fig. 15 is a broken side elevational view corresponding generally to Fig. 1, but with the cutting blade advanced to a desired cutting position on the comb and also disclosing the means for retaining lubricant wicks and their operative relation to the comb and blade working surface;

Fig. 16 is a view generally similar to Fig. 1, but disclosing a modified embodiment of the invention, the oscillatory cutting blade being shown in maximum advanced position for cooperation with the outer pointed tip portions of the comb as a clipper;

Fig. 17 is a sectional view substantially in the plane of line 17—17, on Fig. 16;

Fig. 18 is a partial transverse sectional view of the supporting frame and carriage;

Fig. 19 is a sectional view, on a reduced scale, in the plane of line 19—19, on Fig. 16, and showing the forward or outer face of the modified vibratory plate to which the cutter blade oscillating mechanism is attached.

Referring now in detail to the drawings, and referring first to Figs. 1 to 5 thereof, a mechanism supporting head is provided and which comprises a supporting or base plate 10. This plate extends transversely of and is suitably secured to the forward end of the usual handle forming housing H, which may be connected to a power operating mechanism. This mechanism is usually an electric motor of well known form and in the instant case includes a rotary shaft S carrying an eccentric pin P at its forward end.

The base plate 10 is provided with an aperture 11 which receives this forward end of shaft S. The eccentric pin P projects through this aperture with its free end a substantial distance from the forward face of the plate 10, as is shown in Fig. 1.

The head further includes opposite side flanges 12 which may be integral with or suitably rigidly secured to the opposite ends of the base plate 10.

Rigidly secured to the lower edge of the base plate 10, as by screws 13, is a track bar 14 and which bar is provided in its upper face with a V-groove forming a track or slide 15 for a purpose later referred to.

Disposed adjacent the upper edge of the base plate 10 is a roller 16 provided with a transversely arcuate circumferential groove 17 whose center line is preferably in the vertical plane of the apex line of the V-groove 15 in the plate 14.

The roller 16 is rotatably supported on the base plate 10 by any suitable means such as a screw 18 and a washer 19 interposed between the base plate and adjacent face of the roller.

A vibratory plate 20 of insulating material is disposed in advance of the base plate 10 and the lower edge thereof is bevelled, as at 21, for longitudinal sliding engagement with the V-track or slide 15. The vibratory plate 20 is provided with a vertically elongated rectangular opening 22 intermediate its upper and lower edges and which extends entirely through the plate. The outer end of this opening is closed by a plate 23 which is secured to the outer face of vibratory plate 20 as by means of screws 24 and the upper edge of plate 23 terminates in cylindrical portions 25, through which extends a shaft 26.

The shaft 26 projects equidistantly beyond the outer-

most ends of the cylindrical portions 25 and is rigidly supported therein. The major central portion of this shaft 26 conforms with and is received in the roller groove 17 for axial supported movement thereof. It will be observed from the above description that by the provision of the linear track or slide 15 and the anti-friction roller 16, together with the cooperating bevelled edge 21 and shaft 26 of the vibratory plate 20, said plate 20 is freely guided for movement transversely of the head, or lengthwise of the base plate 10.

The vibratory plate 20 is preferably provided with resilient bearing plates 27, e. g. leaf springs, at the opposite vertical sides of the central opening 22 and which are engaged by pin P in its eccentric movement to thereby impart comparatively noiseless oscillation to the plate 20. The bearing plates 27 may be retained in position as by means of small rivets, screws, or the like, designated 28.

The plate 23 is provided with a stop tongue 29 having a transversely elongated free end portion 30 which will be later referred to.

By forming the plate 20 of insulating or non-conducting material, the device is rendered wholly immune to electrical shocks as may otherwise be experienced both from the handle H and the combing and clipping mechanisms.

At this point, it is to be noted that while the mechanism for imparting vibration to plate 20 is shown as embodying a rotary shaft having an eccentric pin, the improved barbershop device is capable of use with other forms of power mechanism for imparting vibration to the plate 20.

A comb 31 is rigidly secured to the lower projecting end portions of the flanges 12, as by screws 32a (Fig. 6) to extend transversely between these projecting flange ends. This comb includes a solid rear non-cutting base area 32 and a forward long toothed cutting area 33. The upper face of the entire comb is plane and is disposed in substantially 30 degree relation to the axis of the handle H, or 60 degree relation to the base plate 10. However, this angle may vary as will appear in the disclosure of the second embodiment of the invention.

A cutter blade advancing and retracting plate 34, is provided at its upper edge with ears or cylindrical portions 35 which are spaced to freely receive the opposite projecting ends of shaft 26 and abut the adjacent ends of the cylindrical portions 25, whereby the plate 34 is transversely movable with plate 20 and is also swingable toward and away from the plate 20, that is, in a direction lengthwise of the teeth 33 of comb 31.

This control plate 34 is provided with a centrally arranged vertically disposed notch 36 extending inwardly from its upper edge and through which the tongue 29 projects. This tongue has a transversely elongated free end portion 30 which is engageable with the plate 34 at opposite sides of the notch, as is indicated in dotted lines in Fig. 1, for limiting the forward swinging movement of the advancing and retracting plate for reasons which will later appear.

The lower edge of plate 34 is also provided with spaced ears or cylindrical portions 37 which receive the opposite ends of a transverse shaft 38. A pair of fingers 39 are rotatably supported on the central portion of this shaft 38 and include spaced cylindrical shaft-receiving cylindrical portions 40, disposed between the cylindrical portions 37 and abut the inner opposed ends thereof. These abutting cylindrical portions 37 and 40 are preferably provided with cooperating shoulders 41 to limit movement of the fingers 39 in the direction of the comb 31, see Figs. 1 and 3.

These fingers 39 are yieldably urged in the direction of the comb by means of a spring 42 which includes, an intermediate loop portion 43 engaged with the lower edge of plate 34, coil portions 44 encircling the central portion of the shaft 38, and terminal portions 45 extending over the fingers 39 and engaged in apertures 46 therein. The

fingers 39 are further provided with downwardly extended reduced free ends 47 for a purpose about to appear.

A light weight cutter blade 48 (shown in detail in Figs. 10 to 13) includes an elongated body which extends transversely of the comb body and teeth on which it is slidably supported. The blade body is preferably pressed from sheet metal and includes a relatively narrow plane rear edge portion 49, a forward edge or "toothed" portion 50 and an intermediate outwardly arched portion 51.

The arched portion 51 is provided with a pair of transversely spaced apertures 52 which removably receive the reduced free pointed ends 47 of the fingers 39.

With particular reference to Figs. 10 to 13, it is to be observed that the forward edge portion of the cutting blade 48 is provided with alternating short and long notches 53 and 54 respectively. The notches 53 are formed in the free edge of the arched body portion 51 of the blade and the notches 54 are formed in ridged portions 51a projecting downwardly from the main arched body portion, the lower free edges of the ridged portions are ground flat for accurate seating engagement on the plane surface of the comb which results in two way cutting edges on the margins of the notches 54 as is indicated in Fig. 11. This form of cutting blade not only provides for economical manufacture, but also provides a blade of minimum weight with spaced bearing surfaces, therefore assuring more accurate bearing engagement with the working surface of the comb. Furthermore, this particular form of blade, due to its sheet metal structure and limited bearing surface, greatly reduces frictional heat with a consequent reduction in wear of cooperating blade and comb surfaces. The transversely arched portion of the sheet metal blade also aids in removing frictional heat by permitting air to circulate between the major portions of the blade and the working surface of the comb, as well as reducing the area of contact between the blade 48 and the comb 31.

A manually operable member is provided for moving and swinging the plate 34 about the axle of shaft 26 for corresponding movement of the cutter blade 48 toward or away from the pointed free ends of the comb teeth 33 and such means in a preferred form comprises a plate 60 having laterally disposed ears 61 disposed immediately within the flanges 12 and pivotally secured thereto by screws 62 co-axially with shaft 26.

Opposite side arms 63 depend from the finger plate 60 and extend along opposite edges of plate 34 (Fig. 5) and these arms at their lower ends are provided with projections 64 and 65 which engage inner and outer faces of the plate 34 respectively adjacent the opposite edges thereof. These side arms 63 may be made of resilient material to minimize vibration felt on the plate 60.

The manually operated plate 60 and therewith the control plate 34 and cutting blade 51 are normally retracted to their rearmost inoperative position, as in Fig. 1, by means of a pair of coil springs 66, one at each edge of the plate. One end of each spring 66 is connected to an eye 67 carried by a respective flange 12 and the other end thereof is secured to an eye 68 carried by a respective finger plate arm 63 rearwardly of the corresponding projection 64.

While in Figs. 1 to 5 the comb 31 is shown as being relatively thick and having a convexed lower face, it is essential only that the fixed comb have a substantial body portion with long teeth providing a plane upper working surface and accordingly a comb of the general form of an ordinary barber's comb may be employed. Such a form is therefore illustrated in Figs. 7, 8, and 9 and designated 31a.

The invention further includes novel lubricating means and for a disclosure of same, reference will be had to Figs. 14 and 15.

As indicated in these figures, the cutter blade advancing and retracting plate 34 is provided with a yieldable tongue 70, adjacent each edge and on the rear face thereof. These tongues may be separate metal strips suitably se-

cured to the plate 34 as shown, or they may be struck out of the body of the plate. Irrespective of how the tongues are formed, they are so disposed as to have their lower free ends opposed to the cylindrical portions 37 and the upper ends of suitable oil carrying wicks of felt strips 71 are frictionally retained between these tongues 70 and the cylindrical portions 37.

With this arrangement, the lower ends of the wicks or strips will be dragged over the working surface of the comb for distances equal to one half the length of the comb, as well as shorter distances transversely of the comb as is occasioned by cutting oscillation of the plate 34. However, the blade will pick up oil delivered by the wicks and eventually spread it over the entire working surface of the comb.

Having described the structure of the first embodiment of the improved barbering device, the operation thereof is as follows:

The cutting blade 48 and advancing and retracting plate 34 are normally in the position indicated by solid lines in Fig. 1. The power mechanism is set into operation with a resulting rotation of shaft S and the rotation of pin P about the axis of the shaft. The pin P in its circular orbit of rotation will engage the yieldable plates 27 and thereby impart quiet lateral or vibratory movement to the plate 20 and through the connections, previously described, the control plate 34, together with the cutting blade 48, will be oscillated.

The blade 48 will, however, be normally maintained on the solid or toothless and non-cutting surface area of the comb body by action of the springs 66 and even though the blade is undergoing the same oscillatory movement that it does in a cutting operation, it nevertheless is inoperative to cut in that it is not opposed to the comb teeth.

In this normal non-cutting position of the blade, the device functions as a comb only and it may be thus drawn through the hair *h* on a scalp *s* as in Fig. 8 with the working surface of the comb being at such angle and spaced relation to the scalp as duplicates any particular cut surface desired.

The operator has clear vision of the hair projecting above the working surface of the comb and upon which he safely relies in most of the operations in obtaining the desired finished cut.

After having combed and picked up the hair, as in Fig. 8, and while the blade is oscillating, the operator presses rearwardly on upper end of plate 60 with a resulting forward swinging movement of the advancing and retracting plate 34 thereby advancing the cutter blade 48 outwardly over the plane toothed surface of the comb. If the blade is moved forwardly to the free ends of the comb teeth, as in Fig. 9, all the hair which in Fig. 8 protrudes through the comb, will be cut off.

It will be noted that it is also possible to advance and hold the oscillating blade at any desired position on the comb for evening or shading the hair or while cutting the hair very short around the back of the neck and temples, or to hold it in its full extended clipping position. By pressure on the blade advancing lever the vibrating

blade may be moved at will and held at any position between the extreme positions shown in Figs. 8 and 9.

The springs 66 are just strong enough to maintain the cutting blade in the solid line position in Fig. 1, and very little effort is required to move the oscillating blade forwardly over the comb teeth through the manually engageable plate or lever 60.

It is to be noted that while the working surface of the comb is in a fixed plane, the shaft 38 supporting the fingers 39 moves in an arc with the axis of shaft 26 as its center.

Accordingly, the axis of shaft 38 is at variable distances from the comb working surface in the fore and aft movement of the blade. However, the spring 42 urges the ends 47 of the fingers 39 downwardly with substan-

tially uniform pressure in all ranges of such fore and aft movement with a resulting uniform pressure between the comb and blade working surfaces.

Since the blade is maintained in working position by the loose engagement of the finger ends 47 therewith, the blade is capable of ready removal upon slight lifting of the finger ends 47.

Reference will now be had to Figs. 16 to 19, wherein there is disclosed the second embodiment of the invention. While the structure of this modified embodiment provides the same general operation as the first embodiment, it differs therefrom essentially in the provision of cutting blade supporting and operating mechanism which is movable in two directions in a plane parallel to the working surface of the comb, thereby eliminating the swinging plates of the first embodiment.

As indicated in Fig. 16, the supporting plate 10, having the aperture 11 and receiving the shaft S as in the first embodiment, is provided. The plate 10, however, is provided with a pair of laterally spaced arcuately grooved rollers 75 adjacent its upper edge and a second pair of arcuately grooved rollers 76 adjacent its lower edge which are respectively vertically aligned with the upper rollers.

A vibratory plate 20a of electrical insulating material is disposed forwardly of the supporting plate 10. This plate has upper and lower outwardly convex edges which are transversely aligned with the grooves in the upper and lower rollers 75 and 76, for free lateral vibratory movement of the plate 20a, similar to the vibratory movement of the plate 20 in the first embodiment of the invention.

The plate 20a rigidly supports a frame member 77 which embodies an upwardly directed tongue plate 78. This tongue plate spans the pin receiving opening 22 and is rigidly secured to the plate 20a as by means of four rivets 79.

The frame further embodies a top plate 80 as a forward extension of tongue plate 78 and which is provided with a relatively large clearance recess 81 for a purpose later to appear.

It will be seen that the frame 77 also embodies laterally disposed guide or track portions 82 which are of substantially closed form and which are integral with top plate 80, as is clearly shown in Fig. 18.

This frame 77 as just described and including the track members 82, is disposed above the plane working surface of the comb 31, and the plate 80 thereof is in spaced relation to the surface and parallel thereto.

At this point, it is to be noted that the frame 77 and the working plane surface of the comb 31 are at substantially a 45 degree angle to the base plate 10, instead of a 60 degree angle as in the first embodiment.

However, such angle may be varied within limits without in any way affecting the intended operation of the device.

The frame 77 will have oscillatory movement transversely to the teeth of comb 31, but will have no movement in a direction lengthwise of the teeth.

A carriage 83 is supported within the frame 77 and it includes a plate 84. This plate 84 is supported by casters 85 which are disposed within the track 82 and have a rolling contact. As shown in Fig. 16, the lower caster is in contact with the lower flange of the track, whereas the upper caster would be in contact with the upper flange of the track. This is because the fingers 101 which press on the cutting blade 48, are lifting or supporting the upper end of the carriage due to the tension adjusting spring 103. Fig. 18 shows the lower caster in contact with the lower flange of the track.

Means are provided for imparting movement to the carriage 83, in a direction lengthwise of the teeth of the comb 31 and such means preferably comprise a platform lever 87 having ears 88 at the opposite side edges thereof. These ears are pivotally connected to the flanges 12 immediately within same, as indicated at 89.

The plate lever 87 extends downwardly from the ears 75

and terminates in advance of the front end of carriage 83, as illustrated in Fig. 16.

A pair of connectors 90 (preferably flexible cable) extend rearwardly from the lever 87 and are disposed beneath the plate 84 of the carriage 83. These connectors have their forward ends secured to the lever 87, as at 91, and have their rear ends secured to the carriage, as at 92.

The upper end of the cutter advancing lever 87 is provided with an upwardly arched finger engageable portion 93.

Downward pressure on this portion will through the connectors 90 move the carriage forwardly and the carriage is limited in its forward movement by suitable means such as pins 94 engageable with the ears 88, as illustrated in Fig. 16.

The carriage 83 is normally urged to a rearward position by means of a coil spring 95, whose forward end is connected to a depending lug 96 on the carriage.

The rear end of the spring is connected to a tongue 97 which extends forwardly of an apron 97a which in turn extends from one to the other of the side flanges 12.

A yieldable plate 98 is disposed beneath the carriage 83 and has an upwardly directed tongue 99 at its rear end and which is pivotally connected at 100 to the rear end of the carriage in the longitudinal center line thereof.

The forward end of the plate 98 is bifurcated in the provision of a pair of tongues 101 whose extremities are rounded and directed downwardly in the form of reduced ends 102. These rounded free ends 102 are loosely received in apertures 52 in the upwardly arched portion of the cutting blade 48.

In order to maintain the cutting blade in firm engagement with the working surface of comb 31, the plate 98 is yieldably urged, downwardly by means of a coil spring 103, whose lower end engages the upper surface of the plate and which upper end engages a screw plug 104. The screw plug 104 is adjustably threaded in an internally threaded sleeve 105 extending through and projecting above, the plate 84 of the carriage 83. The recess 81, in the frame plate 80, accommodates this plug 104 upon rearward movement of the carriage 83.

The operation of the modified construction as above described, is similar to that of the first embodiment.

The frame 77, carriage 83, and cutting blade 48 will be reciprocated laterally of the comb teeth irrespective of the controlled position of the cutting blade lengthwise of the teeth of the comb. Therefore, by the co-action of the finger controls plate lever 87 and the spring 95 the oscillating blade 48 may be positioned anywhere on the working surface of the comb. This means that the power operating blade may be moved at will from the maximum advanced position shown in Fig. 16 to a non-cutting position on the solid portion of the comb, as well as at intermediate points.

The spring 95 is of sufficient strength to normally urge and hold the blade in its rear non-cutting position, similar to the position illustrated in Figs. 1 and 8.

While the levers 60 and 87 are shown in position to be engaged by a finger or thumb, these levers may be relocated or linked so that a squeezing pressure exerted by the hand will regulate the movement of the cutting blade fore and aft over the rigid comb.

One thing my invention has done is to bring into one simple fool-proof implement the means whereby an operator can do the things a barber does with two hands, namely, place a comb in position to elevate a portion only of the hair into cutting position and then cut off this projecting hair while the comb-like member holds it supported. Because the time of making the cut is in the control of the operator, he or she has ample opportunity to consider each intended cut and the effect it will produce before advancing the cutting member over the comb-like member to make the cut. In other words, the cutting member can be reciprocating from side to side over the

solid portion of the planar surface of the comb-like member, all the while the operator is moving the teeth of the comb-like member into position to make a cut, without any risk of making a cut (see Fig. 8) and then when the operator is satisfied that he or she has the comb-like member in correct supporting position for the unwanted hair, the manual means is actuated to cause the reciprocating cutting member to move out over the teeth of the comb-like member to sever the supported hair (see Fig. 9). As the manual means is released the cutting member moves back into its non-cutting position to await the operator's decision as to the next cut.

What I claim:

1. In a hair cutting device, a supporting base, a comb rigidly supported by the base and having a working surface, said working surface including a rear solid portion and a front toothed portion, a cutting blade supported on said working surface of the comb, pivoted means movable in relation to the base and connected to said cutting blade for moving same along said working surface lengthwise of the teeth of said comb, vibratory means operably engaged with said pivoted means for oscillating same and the blade on said working surface transversely of the teeth of said comb, and manually actuatable means engaged with said pivoted means for effecting said lengthwise movement along said solid and toothed portions simultaneously with the oscillation of the pivoted means.

2. In a hair cutting device, a supporting head, a long toothed comb rigidly supported by the head and having a plane working surface, a cutting blade mounted on said working surface, a swingable member pivotally connected to the head on an axis transverse to the comb teeth and pivotally engaging said cutting blade, manually actuatable means engaged with said swingable member for moving said swingable member and said cutting blade to and fro lengthwise of the comb teeth in any desired position between free and base ends of the comb teeth, and means operatively engaged with the swingable member for imparting vibratory movement thereto and to the blade transversely of the comb teeth in any position of the swingable member lengthwise of the teeth.

3. The structure according to claim 2 wherein said comb includes a relatively wide substantially solid portion having a surface in said plane, and yieldable means engaged with said swingable member for normally holding said cutting blade on said solid portion.

4. The structure according to claim 2 wherein said pivotal engagement between said swingable member and said cutting blade comprises a pair of fingers having corresponding ends thereof pivotally connected to the swingable member, yieldable means urging said fingers toward the free ends of said fingers and said cutting blade whereby a three-point pivotal relation is provided between said vibrating swingable member and said cutting blade to maintain a uniform pressure of the cutting blade against the comb in any of its to and fro positions.

5. In a hair cutting device, a supporting plate having an aperture therein for projection therethrough of powered mechanism for imparting vibration, upper and lower guide ways supported on the front face of said plate, a vibratory plate guidingly disposed between said guide ways and having operative connection with said mechanism, a swingable plate pivotally connected at its upper edge to said vibratory plate, a long toothed comb rigidly supported by said supporting plate and having a plane working surface disposed at an obtuse angle to said supporting and vibratory plates, a cutting blade supported on said working surface and operative engagements between the lower edge of said swingable plate and said cutting blade so that pivotal movement of said swingable plate will move said cutting blade in a cutting stroke longitudinally of the teeth of said comb.

6. In a hair cutting device a supporting head, a long toothed comb rigidly supported by the head, a plate guid-

ingly supported by the head for oscillatory movement transversely of the teeth of the comb, means supported by the plate for oscillatory movement therewith and being freely movable lengthwise of said teeth, said supported means comprising a frame rigidly connected to said plate and having a pair of spaced parallel tracks extending above and parallel with the teeth of said comb and a carriage including wheels engaged with said track, and manually actuatable means operatively engaged with said supported means moving said supported means lengthwise of said teeth independently of the oscillation of said plate.

7. The structure according to claim 6 wherein said manually actuatable means comprises a plate-like lever pivotally connected adjacent one end thereof to said supporting head and pivotally connected adjacent its opposite end to said carriage.

8. The structure according to claim 6 together with an elongated coiled spring having one end thereof connected 15 to said supporting head and the opposite end thereof connected to said carriage for normally holding the carriage in rear position and yieldably resisting movement thereof toward the ends of said teeth by said second means.

9. In a hair cutting device: a supporting base; a long toothed comb rigidly supported by the base; a vibratory frame member slidably mounted on said supporting base and having a forwardly extending portion; means to vibrate said frame member; guide means carried by said 20 extending portion; a cutter blade mounted for sliding movement on said comb; carriage means supported by said guide means coacting with said cutter blade to permit movement of the blade relative to the vibratory frame member, and manually operable means pivotally mounted on said base and operatively connected to said carriage means to move the cutter blade longitudinally of said comb teeth as the blade vibrates transversely due to the vibration of said frame member.

10. In a hair clipper, a frame supported operating mechanism including a vibrating member, a hair penetrating comb rigidly secured to the frame, a blade freely slidable on the comb between opposite sides thereof as well as from the outer free edge to the base of the comb, said blade being pivotally connected to the vibrating member to vibrate against the comb in a cutting operation, and manual means co-operating with said pivotal connection to advance and retract said blade, as it vibrates, toward and from said free edge and for holding same in any position between said free edge and base of the comb.

11. In a hair cutting device; a supporting base; a long toothed comb rigidly supported by the base and having a working surface, said working surface including comb teeth having free and base ends; a vibratory member slidably mounted on said supporting base; a cutting blade 55 on the working surface of the comb; a swingable member pivotally connected to the vibratory member to vibrate therewith and operatively engaged with said cutting blade; manually operable means engaged with said swingable member for moving said swingable member and said cutting blade to and fro lengthwise of the comb teeth to any desired position of the blade between the free and base ends of the comb teeth; said vibratory member imparting vibratory movement to the swingable member and to said blade transversely of the comb teeth in any position of the swingable member lengthwise of said comb teeth.

12. The structure according to claim 11 wherein the manually operable means is pivotally connected to said base and slidably engages said swingable member, whereby the vibratory motion of the swingable member is not imparted to the manually operable means.

13. The structure according to claim 11 wherein said comb includes a relatively wide substantially solid portion 70 forming a part of said working surface and yieldable

means engaged with said swingable member for normally holding said cutting blade on said solid portion.

14. The structure according to claim 11 wherein said operative engagement between said swingable member and said cutting blade comprises a pair of fingers having corresponding ends thereof pivotally connected to the swingable member, yieldable means urging said fingers toward the cutting blade, and universal connections between the free ends of said fingers and said cutting blade, whereby a three point pivotal relation is provided between said vibratory member and said cutting blade to maintain a uniform pressure of the cutter blade against the comb in any of its to and fro positions.

15. In a hair clipper; a frame supported operating mechanism including a vibrating member; a comb rigidly secured to the frame having a base, an outer free edge, and an intermediate working surface; a blade pivotally connected to the vibrating member and freely slidable on the comb, said blade being thin with respect to its area and having a curved contour, concave to the comb working surface, and with a fluted cutting edge terminating in cutting teeth, whereby a minimum bearing surface is provided while retaining the rigidity and strength required of the cutting blade; and manually operated means for advancing and retracting said blade toward and from said free edge and for holding same in any position between said free edge and base of the comb.

16. In a hair cutting device, wherein vibratory means are provided to impart a rapid reciprocatory motion to a cutting blade slidably mounted above a fixed comb, the combination of a supporting base, said comb being rigidly supported by the base and having a working surface, said working surface including a rear solid portion and a front toothed portion terminating at the outer free ends of said teeth, manually operable means for moving said cutting blade in a longitudinal cutting stroke along said comb teeth, spring means for normally holding said cutting blade in a non-hair cutting position on the solid portion of said comb, and outer stop means for limiting the longitudinal cutting stroke of said cutting blade to a point adjacent the outer free ends of said comb teeth.

17. In a hair cutting device; a supporting base; a long toothed comb rigidly supported by the base and having a working surface; a vibratory member slidably mounted on said supporting base; a cutting blade on the working surface of the comb; a swingable member pivotally connected to the vibratory member to vibrate therewith and operatively engaged with said cutting blade; manually operable means pivotally connected to said base and slidably engaging said swingable member for moving said swingable member and said cutting blade to and fro lengthwise of the comb teeth in a cutting stroke, said respective pivotal connections of the swingable member and the manually operable means being in axial alignment; outer stop means for limiting said cutting stroke; and resilient means for normally holding said manually operable means, swingable member, and cutting blade in a retracted non-hair cutting position on a solid portion of the comb working surface; whereby on actuating said manually operable means said vibratory member continues to impart vibratory movement to the swingable member and to said blade in any position of the swingable member lengthwise of said comb teeth.

18. A hair clipper comprising a frame supported blade vibrating mechanism, a long toothed comb rigid with said frame and projecting from one side thereof, the cutting edges of said long teeth being in a common plane, and the opposite edges being rounded and tapering from the outer pointed ends of the teeth to their juncture with the base of the comb, a cutter blade having teeth relatively shorter with respect to the comb teeth slidably mounted on the plane surface of the comb and connected by a swingable mounting to said vibrating mechanism for transverse movement thereof on said comb, said cutter blade being freely movable with its swingable mounting longitudinally from the pointed ends of the comb teeth to the base joined ends thereof, and manually operable means cooperating with said swingable mounting and pivotally mounted on said frame and swingable over the plane surface of said comb to advance, retract or hold said cutter blade at any desired point between the free ends and base of the comb teeth, whereby the cutter blade may be positioned on the comb edges at any desired angle with respect to a head of hair prior to advancing said blade in a cutting stroke along the comb teeth.
19. In a hair cutting device, a supporting head; a long toothed comb rigidly supported by the head and having a relatively wide substantially solid portion at the base of the teeth; a cutting blade mounted adjacent said comb; a swingable member pivotally connected to the head on an axis transverse to the comb teeth and operatively engaged with said cutting blade; yieldable means engaged with said swingable member for normally holding said cutting blade on said solid portion; manually actuatable means engaged with said swingable member for moving said swingable member and said cutting blade to and fro lengthwise of the comb teeth in any desired position between the free and base ends of the comb teeth; and means operatively engaged with the swingable member for imparting vibratory movement thereto and to the blade transversely of the comb teeth in any position of the swingable member lengthwise of the teeth.
20. A hair cutting implement having a comb-like member with cutting edges bordering the teeth of said member, a guide member mounted for lateral movement adjacent said comb-like member, a carriage mounted in said guide member for lateral movement therewith and for longitudinal movement relative thereto adjacent said comb-like member; a cutter member operatively connected to said carriage and movable over and in contact with the cutting edges of the teeth of said comb-like member; means for laterally vibrating said guide member, thereby vibrating said carriage and said cutter member; and manually operated means for varying the longitudinal position of said carriage, thereby moving said cutter member longitudinally over said teeth as it vibrates.
